SALESBOOK AND HOLDER

Harold W. Clark, Alliance, Ohio, assignor to The McCaskey Register Company, Alliance, Ohio, a corporation of Ohio

Application March 26, 1937, Serial No. 133,152

9 Claims. (Cl. 282—8)

The invention relates to manifold salesbooks and holders therefor and more particularly to a salesbook and holder adapted to be used as a portable autographic register such as disclosed in my prior Patent No. 1,913,190, granted June 6, 1933.

The purpose of such devices generally is to combine the advantages of the two methods now commonly used for writing plural copies of sales slips when a purchase is made, namely the manifold salesbook and the autographic register.

The manifold salesbook, which is the older of the two devices for writing plural copies of sales slips, has the advantage of being easily portable, light in weight and inexpensive in construction, although it is more or less unhandy to use and not entirely satisfactory for making sharp clear copies.

The autographic register, although comparatively expensive and not readily portable, like the salesbook, because of its size and weight, is easily operated and is provided with a writing table or bed which permits the making of sharp clear copies of the sales slips.

The combined advantages of these two devices are generally attained in my prior patent above referred to and the present invention is an improvement upon such devices which provides for more easily and readily inserting the salesbook into the holder and for greater ease and rapidity of operation.

An object of the present improvement is to provide a salesbook and holder therefor with cooperating means for causing the salesbook to be locked against accidental displacement as it is inserted into the holder.

Another object is to provide a salesbook and holder therefor so constructed that the salesbook is pivotally connected to the holder in such a manner that by a slight tilting of the holder the salesbook will by gravity swing out to one side so that the uppermost set of sales slips or leaves in the book may be quickly and easily placed over the writing table of the holder and by tilting the holder in the opposite direction the salesbook will slide back into normal position with the upper set of slips thereof properly positioned over the writing bed.

A further object is to provide means for limiting the movement of the salesbook relative to the holder in each direction.

Another object is to provide means whereby the uppermost set of sales slips may be quickly and easily severed from the book, along the usual

perforated or weakened line, by a downward pressure upon the upper end of the salesbook.

The above and other objects may be attained by providing a holder having a compartment open at two adjoining sides and a plate pivotally mounted within the compartment and adapted to swing outward through one of the open sides; there being cooperating means upon the plate and the salesbook for attaching one end portion of the salesbook to the plate, the other end portion of the salesbook extending through the other open side of the compartment, means being provided for limiting the movement of the plate in each direction relative to the holder.

An embodiment of the invention thus set forth in general terms is illustrated in the accompanying drawings, in which

Figure 1 is a perspective view of the improved holder with the salesbook mounted therein;

Fig. 2 is a top plan view of the holder with the salesbook in writing position therein;

Fig. 3, a top plan view of the holder with the salesbook swung outward through one open side thereof preparatory to placing the uppermost set of sales slips over the writing table of the holder;

Fig. 4 is a plan sectional view of the holder with the salesbook removed, showing the pivoted plate therein;

Fig. 5, a plan view of the improved salesbook with the lower portion of the leaves or sales slips turned back to disclose the slot in the back of the salesbook;

Fig. 6, a longitudinal sectional view through the holder showing the manner in which the salesbook is locked to the pivoted plate;

Fig. 7, a side elevation of the holder and salesbook showing the manner in which the uppermost set of sales slips may be quickly sheared from the salesbook by downward pressure upon the upper end of the salesbook; and

Fig. 8, a transverse sectional view through the holder and salesbook, taken as on the line 8—8, Fig. 6.

Similar numerals refer to similar parts throughout the drawings.

The improved salesbook holder to which the invention pertains may be formed of any suitable material, preferably being molded from a plastic material such as bakelite or the like. This holder may comprise generally a top wall forming a writing table or bed 10 and a bottom wall 11 preferably of slightly greater length than the top wall, as illustrated in the drawings, providing a compartment 12 adapted to normally house a salesbook as will be later described.

The writing table and bottom wall may be joined along one side and one edge as by the side wall 13 and end wall 14 respectively, the other side and end of the compartment being open as indicated at 15 and 16 respectively.

The book holding plate 17 may be of sheet metal or other suitable material and is located within the closed end portion of the compartment, being pivoted preferably at one corner of the plate, as indicated at 18, adjacent to the open side of the compartment.

For the purpose of limiting the movement of the plate 17 in each direction, relative to the holder, an arcuate slot 19, having its center at the pivot point 18, is formed in the plate 17 and receives a stud 20 carried by the bottom wall 11 of the holder.

An elongated transversely disposed tongue 21 may be struck upwardly from the plate near its inner end, which is turned upward as at 22, forming an angular stop flange. The side edges of the plate may be folded back, forming the flanges 23 producing guide grooves to receive the side edges of the back 24 of the salesbook which may be provided near its free end with a transversely disposed elongated slot 25 adapted to receive the locking tongue 21 of the plate when the side edges of the back are inserted beneath the flanges 23 of the plate.

A plurality of sets of sales slips 26 may be connected to the opposite end portion of the back 24 of the salesbook in usual and well known manner, these sales slips being weakened as by a perforated line 28 adapted to substantially register with the free end edge 29 of the writing table 10 of the holder, when the salesbook is in normal position in the holder as best shown in Figs. 2, 6 and 7.

To insert the salesbook in the holder and lock it against accidental displacement therein, it is only necessary to insert the free end of the salesbook through an open side of the holder, sliding the free end portion of the back 24 over the plate 17 and under the side flanges 23 thereof and as the aperture 25 in the back registers with the tongue 21 of the plate, it will receive the tongue therein, as best shown in Figs. 6 and 8 and further movement of the salesbook will be prevented by contact of the end thereof with the end flange 22 of the plate. The salesbook is thus locked to the plate and cannot be accidentally disconnected therefrom.

In the normal position of the device, the salesbook is located within the holder as best shown in Figs. 1 and 6. In using the device a slight tilting of the holder toward the open side 16 will permit the salesbook to slide outward through said open side to the position shown in Fig. 3. The position to which the pivoted plate 17 swings on this movement is clearly shown in Fig. 4, the stud 20 and arcuate slot 19 cooperating to limit the outward movement of the plate and salesbook.

It should be of course understood that when the plate and salesbook are swung inward to the normal position, the other end of the arcuate slot 19 contacting with the stud 20 limits the movement of the salesbook and plate in this direction also.

As the salesbook swings to the position shown in Fig. 3, the operator may with his thumb slide the uppermost set of sales slips over the top of the writing table 10 and a slight tilting of the holder in the opposite direction will permit the salesbook to slide back to the position best shown in Fig. 2 with the uppermost set of sales slips 26

properly positioned upon the writing table as shown in Fig. 2.

It has been found in practice that the movement of the salesbook and holder from the position shown in Fig. 1 to that shown in Fig. 3 and then to that shown in Fig. 2 may be quickly and easily accomplished in a single rapid operation.

After the writing has been made upon the sales slip, it is only necessary to press downward upon the outer end of the salesbook as shown in Fig. 7, to sever the uppermost set of sales slips from the salesbook along the perforated or scored line 28, the outer end edge 29 of the writing table registering with said weakened line of the sales slips and causing the slips to be quickly and easily severed at this point.

When all of the sales slips in the book have been used, the book may be quickly and easily removed by an outward pull upon the cover which will tear out the inner end of the same beyond the aperture 25, permitting the empty cover to be removed. A new salesbook may then be inserted in the manner above described.

I claim:

1. In combination with a salesbook, a holder provided with a writing table and having a compartment beneath said writing table open at two adjoining sides, the salesbook being pivotally mounted in said compartment for swinging movement outward through said open sides of the holder and back to original position whereby leaves of the salesbook may be positioned above said writing table.

2. In combination with a salesbook, a holder provided with a writing table and having a compartment beneath said writing table open at two adjoining sides, the salesbook being pivotally mounted in said compartment for swinging movement outward through said open sides of the holder and back to original position whereby leaves of the salesbook may be positioned above said writing table, and means for limiting the outward movement of the salesbook.

3. In combination with a salesbook, a holder provided with a writing table and having a compartment beneath said writing table open at two adjoining sides, a plate pivotally mounted in said compartment, the salesbook being connected to said plate so as to swing outward through said open sides of the holder and back to original position whereby leaves of the salesbook may be positioned above said writing table.

4. In combination with a salesbook, a holder provided with a writing table and having a compartment beneath said writing table open at two adjoining sides, a plate pivotally mounted in said compartment, the salesbook being connected to said plate so as to swing outward through said open sides of the holder and back to original position whereby leaves of the salesbook may be positioned above said writing table, and cooperating means between the salesbook and plate for preventing disconnection of the book intact from the plate.

5. In combination with a salesbook, a holder provided with a writing table and having a compartment beneath said writing table open at two adjoining sides, a plate pivotally mounted in said compartment, the salesbook being connected to said plate so as to swing outward through said open sides of the holder and back to original position whereby leaves of the salesbook may be positioned above said writing table, a tongue upon said plate, the salesbook having a back provided with an aperture to receive said tongue.

HAROLD W. CLARK.
